UNITED STATES PATENT OFFICE

EDWARD CRAIG, OF ST. JOSEPH, MICHIGAN; THE COMMERCIAL NATIONAL BANK, EXECUTOR OF SAID EDWARD CRAIG, DECEASED, ASSIGNOR TO SARANAC MACHINE COMPANY, OF BENTON HARBOR, MICHIGAN, A CORPORATION OF MICHIGAN

MACHINE FOR MAKING BOXES

Application filed March 22, 1928. Serial No. 263,887.

This invention relates to machinery for making boxes or receptacles or containers, and more particularly to machinery for making boxes from paper or pulp board, or other sheet material, such as suit boxes or the like, which are made and shipped in flat condition, but which can then be quickly reduced to box form for use.

Generally stated, therefore, the object of the invention is to provide a machine which will be capable of automatically feeding and folding a box blank and of stapling the blank in folded condition, whereby the desired box is produced in finished condition, but in flat form, so that boxes of this kind can be economically shipped in practically solid stacks or bundles, but whereby each collapsed box can then be unfolded, and reduced to box form for use.

It is also an object to provide certain details and features of construction and combinations tending to increase the general efficiency and the desirability of a box blank folding and stapling machine of this particular character.

To these and other useful ends, the invention consists in the matters hereinafter set forth and claimed, and shown in the accompanying drawings, in which,—

Fig. 1 is a diagrammatic plan of a box blank folding and stapling machine embodying the principles of the invention.

Fig. 2 is an enlarged, vertical, transverse section on line 2—2 in Fig. 1.

Fig. 3 is a similar section on line 3—3 in Fig. 1.

Fig. 4 is an enlarged plan view of the first section of said machine.

Fig. 5 is a longitudinal section on line 5—5 in Fig. 4.

Fig. 6 is an enlarged plan view of the second section of the said machine.

Fig. 7 is a longitudinal, vertical section on line 7—7 in Fig. 6.

Fig. 8 is an enlarged plan view of one of the box blanks.

Fig. 9 is a similar view, showing the first step in the folding and stapling of said blank.

Fig. 10 is a similar view, showing the second step in the folding and stapling of said blank.

Fig. 11 is a perspective of the box formed by unfolding the collapsed or flattened box structure shown in Fig. 10 of the drawings.

As thus illustrated, the box blanks which are fed into the machine are of the kind shown in Fig. 8, each blank being provided with a rectangular bottom section 1, rectangular side sections 2, rectangular end wall sections 3, corner flap sections 4 and 5, and end flaps 6, the said sections and flap portions being formed by the crease lines or score lines 7, 8, 9 and 10, as shown. The first step in the method, as shown in Fig. 9, is to fold under the side walls 2 and the flap portions 4 and 5, and to then insert staples 11 through the end walls 3 and the flap portions 5, as shown. The next step, as shown in Fig. 10, involves the folding under of the end flaps 6 and the insertion of the staples 12 through these flaps and the end walls 3, as shown. This results in a collapsed or flattened box which can be unfolded and reduced to the shape and form shown in Fig. 11 of the drawings.

The machine for practicing the foregoing method comprises a first section consisting preferably of a table 13 upon which the blank is placed longitudinally, as shown in Fig. 4 of the drawings. From this table the blank is pushed forward by a pusher 14 secured to a rod 15 that has its other end connected to the pivoted lever 16, which latter has a roller 17 for engagement with the cam 18 on the shaft 19 of the second section of the machine. This forward feed of the blank will bring its front end between the upper feed belts 20 and the lower feed belts 21, with the side wall sections 2 of the blank under the folder rods 22. It will be understood that it is the spring 23 that actuates the pusher 14 back into its normal position after the cam 18 has actuated the pusher to feed the blank forward. The rods 22 serve to bend the side walls 2 of the blank downward, as shown in Fig. 2 of the drawings. The rods 22 converge forward and terminate in twisted, strap metal folders 24, as shown, and these folders serve to fold the side wall portions 2 of the blank upward against the lower surface of the bottom wall section 1, as shown

in Fig. 3 of the drawings. The upper belts 20 and the lower belts 25 now continue the forward feeding of the blank in this partially folded condition to the table 26, over which 5 are mounted the four staplers 27 for driving the staples 11 previously described. These staplers are actuated simultaneously, through the medium of an eccentric connection 28 on the lower horizontal shaft 29, to drive said 10 staples, said staplers being of any known, suitable or approved form. Before arriving upon the table 26, the partially folded blank has the score lines or crease lines 7 compressed and firmly creased by the rollers 30 15 on the shafts 31 and 32, which support the belt pulleys 33, as shown. During the forward feed of the blank in the first section of the machine, it is forced to travel between the upper and lower rollers 34 and 35, which 20 rollers bear against the upper and lower belts 20, 21 and 25, causing these belts to tightly and frictionally grip the blank and feed it forward.

It will be seen that the table 26 and the 25 staplers 27 belong to the second section of the machine, and that from this table the partially folded blank is fed forward between the upper and lower belts 36 and 37, which are similar to the belts previously described.

30 This forward feed of the partially folded and stapled blank is caused by the engagement of the feed dog 38 with the rear edge 39 of the partially folded and stapled blank (see Fig. 9 of the drawings), which feed dog is 35 on rods 40 actuated by a lever 41 and a connecting rod 42, said lever 41 being in turn actuated by the eccentric device 43 on the shaft 29 previously mentioned. When the partially folded blank is fed upon the table 40 26, it moves endwise between the dog 38 and the other dog 44 on said rods 40, thus positioning the blank in condition to be stapled. After the staples are driven, the feeding 45 and stapling being in properly timed relation, the rods 40 then move backward until the dog 38 engages the rear edge 39 of the partially folded blank, and the rods 40 then move in the opposite direction to feed the blank between the belts 36 and 37. The blank 50 now moves forward with its end flaps 6 below the folding rods 45, which are similar to the rods 22 previously mentioned. These will fold the flaps 6 downward in the desired manner. The rods 45 converge forward and 55 terminate in twisted, strap metal folders 46, which are similar to the folders 24 previously mentioned. These folders 46 will fold the flap 6 upwardly against the lower surface of the end wall sections 3 in a manner that 60 will be readily understood. The blank continues to feed forward between the upper belts 36 and the lower belts 47, rollers 48 and 49 pressing said belts against the upper and lower surfaces of the blanks, to friction feed 65 the blank forward. The rollers 50 and 51 on

the belt pulley shafts 52 and 53 compress the crease lines 10 before the blank arrives on the table 54 of the final stapling machine having the four staplers 55 disposed immediately over said table. These staplers are 70 actuated by an eccentric device 56 on the transverse horizontal shaft 57, in a manner that is common and well known, and said staplers are of any known, suitable or approved form. The staplers 55 now drive the 75 staples 12 and reduce the blank to the form shown in Fig. 10 of the drawings.

Upon the table 26, the blank is kicked forward a slight distance longitudinally thereof by the pusher 58 on the rod 59, this rod being actuated by a lever and link connection 60, which in turn is actuated by a cam 61 on the shaft 29 previously mentioned, and the spring 62 serves to yieldingly keep the pusher 58 in normal position. The dogs 63 on the rods 40 feed the completely folded blank into position below the staplers 55 at the same time that the dogs 38 feed the partially folded blank behind into the feeding belt feed means of the second section of the machine. Also, at such time, the dogs 64 on the rods 40 feed the completely stapled blank off the table 54 to make room for the next blank to be stapled. Thus, it will be seen that the staplers 27 and the staplers 55 operate 90 at the same time, the dogs 38 and 44 and 63 and 64 being in the positions which they occupy at the time that a partially folded blank is fed between the dogs 38 and 44 and at the time that the partially folded blank is feeding between the belts 36 and 37, and at the time that a blank is being stapled by the staplers 55, while at the same time the dogs 64 are just ejecting a finished and flattened or collapsed box. In its entirety, therefore, the folding and stapling machine shown and described is operating simultaneously upon one blank in the feeding instrumentalities shown in Figs. 4 and 5, upon a second blank 100 below the staplers 27, upon a third blank still farther ahead in the feeding instrumentalities shown in Fig. 7, and upon a fourth blank still farther ahead under the staplers 55, whereby four blanks in various stages of folding and stapling are being operated upon at the same time. Also, for every blank taken into the feeding and folding instrumentalities shown in Figs. 4 and 5 of the drawings, a finished and flattened or collapsed box is ejected from the other end of the machine by the dogs 64 previously described.

110 The different folding and stapling instrumentalities can be timed in their operations in any suitable or desired manner, it will be understood, and the machine can be operated by a pulley clutch 65, through the medium of the gearing 66 and the sprocket belts 67 and 68, connected to the feed belt 115 120 125 130

shafts and the operating shafts 29 and 57, in any suitable or desired manner

In Fig. 8 of the drawings, therefore, the arrow 69 indicates the direction of feed of the blank in the first section of the machine. In Fig. 9, the arrow 70 indicates the direction of feed of the partially folded blank in the second section of the machine. Thus it will be seen that the blank first moves endwise, as indicated in Fig. 8, and thereafter moves sidewise in a direction at right angles to its endwise movement. Both movements, however, are in the same horizontal plane, and the box is thus formed and stapled upside down, so to speak, as the bottom section 1 of the box blank is uppermost during the folding and stapling operations.

From the foregoing, it will be seen that the flaps are advantageously folded downward, while the blank is being folded by the means provided for that purpose, and in this way the staples are driven downward and clinched on the inside of the box. Furthermore, the first set of staplers drive one set of staples simultaneously, and the second set of staplers also drive all of the staples of the second set simultaneously. This speeds up production and insures better results.

As shown and described, the machine has 30 staplers for inserting eight staples in each blank, to hold the folded blank in collapsed or folded form, but it will be understood that any desired or preferred number of staples can be driven, depending upon the size of the box to be made. The creasing and folding will be the same, for any size of box, but the number of staples can be varied, by varying the number and location of the staplers, in accordance with the size of the 40 box to be made.

Without disclaiming anything, and without prejudice to any novelty disclosed, what I claim as my invention is:

1. In a machine for folding and stapling box blanks, thereby to produce a stapled box in collapsed or flattened condition, capable of being unfolded into box form, the combination of primary feeding and folding instrumentalities for feeding the box blanks in one direction, having means for partially folding the blanks while traveling in said direction, staplers disposed in position to simultaneously receive and staple the partially folded blanks, secondary feeding and folding instrumentalities for feeding the partially folded and partially stapled blanks in a direction at right angles to said one direction, away from said staplers, said secondary feeding and folding instrumentalities having means for completing the folding of the blanks, and staplers for simultaneously receiving and stapling the completely folded and partially stapled blanks.

2. A structure as specified in claim 1, said 65 primary feeding and folding instrumentalities being adapted to feed the blanks end-

wise, and to fold under the side walls of each blank, and said secondary feeding and folding instrumentalities being adapted to feed the blanks sidewise and fold under the end flaps of each blank.

3. A structure as specified in claim 1, said first-mentioned staplers being disposed in position to insert staples through the end walls and corner flap portions of each blank, and said second-mentioned staplers being disposed in position to insert staples through the end walls and end flaps of each blank.

4. A structure as specified in claim 1, in which the said feeding and folding instrumentalities and the said staplers are so co-ordinated and so relatively arranged that the primary feeding and folding instrumentalities are operating on one blank while the said first mentioned staplers are operating on another blank, and while the secondary feeding and folding instrumentalities are operating on another blank, and while the second mentioned staplers are operating on still another blank.

5. A structure as specified in claim 1, said first mentioned staplers being four in number and being disposed in pairs and with the two pairs spaced a certain distance apart, and the second mentioned staplers being also four in number and disposed in pairs with the two pairs spaced the said certain distance apart, but with the members of each pair of the second mentioned staplers disposed closer together than are the members of each pair of the first mentioned staplers.

6. A structure as specified in claim 1, said first mentioned staplers being disposed in position to insert staples at the corners of an oblong rectangle, and the second mentioned staplers being disposed in position to insert intermediate staples on the shorter lines of said rectangle.

7. A structure as specified in claim 1, in combination with means for automatically feeding the partially folded and partially stapled blanks from said first mentioned staplers to said secondary feeding and folding instrumentalities, together with means for automatically feeding the completely folded but partially stapled blanks from the secondary feeding and folding instrumentalities to the second mentioned staplers.

8. A structure as specified in claim 1, in combination with means for automatically feeding the partially folded and partially stapled blanks from said first mentioned staplers to said secondary feeding and folding instrumentalities, together with means for automatically feeding the completely folded but partially stapled blanks from the secondary feeding and folding instrumentalities to the second mentioned staplers, and means for automatically feeding the flat box

blanks to said primary feeding and folding means.

9. A structure as specified in claim 1, comprising automatic means below said first 5 mentioned staplers to adjust the position of each partially folded blank below these staplers.

10. A structure as specified in claim 1, comprising means for automatically feeding the 10 flat blanks to said primary feeding and folding instrumentalities.

11. A structure as specified in claim 1, comprising means for automatically ejecting the 15 completely folded and stapled and flattened or collapsed boxes from said second mentioned staplers.

12. A structure as specified in claim 1, comprising automatic means for feeding each 20 partially folded and partially stapled blank from the first mentioned staplers to the secondary feeding and folding instrumentalities, and for simultaneously therewith feeding each completely folded but partially 25 stapled blank from said secondary feeding and folding instrumentalities to the second mentioned staplers.

13. In a box folding and stapling machine, the combination of means for folding the 30 side wall flaps of the box blank downward and then upward against the under side of the blank, by motion of the blank parallel with said flaps, leaving the end wall flaps unfolded, and means for inserting staples 35 downward to secure the side wall flaps in folded condition at right angles to said end wall flaps.

14. In a box blank folding and stapling machine, the combination of means for folding 40 outside wall portions of the box blank flatwise upon other portions thereof, by motion of the blank parallel with said outside portion, to form a collapsed or flattened rectangular box, and means for simultaneously 45 driving a set of staples at both ends of the box to hold the folded portions in place.

15. In a machine for folding box blanks, thereby to produce a box in collapsed or flattened condition, capable of being unfolded into box form, the combination of primary 50 feeding and folding instrumentalities for feeding the box blanks in one direction, having means for partially folding the blanks while traveling in said direction, means for fastening the folded portions to unfolded portions, secondary feeding and folding instrumentalities for feeding the partially folded blanks in a direction at right angles to said one direction, said secondary feeding and 55 folding instrumentalities having means for completing the folding of the blanks, and means for fastening the finally folded portions to said unfolded portions.

16. A structure as specified in claim 15, 60 said primary feeding and folding instrumentalities being adapted to feed the blanks end-

wise, and to fold under the side walls of each blank, and said secondary feeding and folding instrumentalities being adapted to feed the blanks sidewise and fold under the end flaps of each blank. 70

17. A structure as specified in claim 15, comprising means for automatically feeding the flat blanks to said primary feeding and folding instrumentalities.

18. A structure as specified in claim 15, 75 comprising means for automatically ejecting the completely folded and flattened or collapsed boxes.

19. A blank-folding and stitching machine comprising primary and secondary sections 80 at an angle to each other; travelling blank-carriers for said sections; folding devices alongside portions of the carrier in the primary section; folding devices alongside portions of the carrier in the secondary section 85 to fold at an angle to the fold in the primary section; and means in the secondary section to secure folded portions of the blanks to other portions thereof.

20. In a machine for folding and stapling 90 box blanks, thereby to produce a stapled box in collapsed or flattened condition, capable of being unfolded into box form, the combination of primary feeding means for feeding a box blank in one direction, means operative 95 by motion of the blank for folding opposite edge portions of the blank downward and then upward beneath unfolded portions of the blank, secondary feeding means for feeding the partially folded blank 100 in a direction transverse of the first named direction, means operative by said second feeding motion of the blank for folding the other two opposite edge portions of the blank downward and then upward beneath unfolded portions of the blank, and means for inserting fastening devices through said last named folded portions and the unfolded portions of the blank above the same. 105

21. A machine for forming flat-folded 110 boxes from blanks having longitudinal and transverse crease lines which form flaps on each edge thereof, the combination of primary travelling blank carriers for moving a blank in one direction, stationary folding 115 members arranged adjacent said carriers to engage the flaps on two opposite edges of the travelling blank and fold the same down and under unfolded portions of the blank, secondary travelling blank carriers adapted to receive and move the partially folded blank in a direction transverse to previously folded portions thereof, stationary folding members arranged adjacent said secondary carriers to engage the flaps on the other two opposite 120 edges of the blank and fold the same down and under unfolded portions of the blank, and means operating in timed relation with said carriers for inserting fastening devices 125 through said last named flaps and the un- 130

- folded portions of the blank above the same.
22. In a machine for folding and stapling box blanks, thereby to produce a stapled box in collapsed or flattened condition, the combination of travelling blank carriers for moving said blanks singly through the machine, stationary folders arranged adjacent said carriers and adapted to fold the side wall flaps of the box blank downward and upward 70
- 10 against the under side of the blank, by motion of the blank parallel with said flaps, leaving the end flaps unfolded, and means for inserting staples downward through said side wall flaps and the unfolded portions of the blank above the same. 80
23. In a machine for folding box blanks, thereby to produce a box in collapsed or flattened condition, capable of being unfolded into box form, the combination of primary 85
- 20 sections and secondary sections arranged at an angle to each other, a platform between said sections, travelling blank carriers for said primary section, a stationary folding member arranged adjacent each side of said 90
- 25 last named carriers and positioned to fold the flaps on two opposite sides of a blank down and under the blank during the travel thereof, said last named carriers being arranged to deliver partially folded blanks to said 95
- 30 platform, travelling blank carriers arranged to receive partially folded blanks from said platform and move the same through said secondary portion of the machine, a stationary folding member arranged adjacent each 100
- 35 side of said last named carriers and positioned to fold the flaps on the other two opposite sides of a blank down and under the blank during the travel thereof, and means operating in timed relation with said travelling 105
- 40 carriers in the primary and secondary sections of the machine and arranged to insert fastening devices downwardly through said last mentioned folded flaps and the unfolded portions of the blank above the same. 110
- 45 24. In a machine for folding into flat condition box blanks having flaps on each edge thereof, the combination of travelling carriers for moving a blank, stationary folding members arranged to engage the flaps on two 115
- 50 opposite sides of the blank during the travel thereof and fold such flaps downward and upward beneath unfolded portions of the blank, each of said folding members having its terminal portion formed of a strip of flat 120
- 55 metal twisted on its longitudinal axis and arranged to bend the inturned flaps upwardly under the overlying portions of the blank, and means for inserting fastening devices through said folded flaps and the unfolded 125
- 60 portions of the blank above the same.
25. A machine for producing flat folded cartons having weakened transverse lines, said machine having means for folding marginal portions of the blanks against other 130
- 65 portions thereof, said folding being longi-
